ELECTRIC GLOW DISCHARGE TUBE

Application filed March 12, 1931, Serial No. 522,122, and in Germany April 2, 1930.

This invention relates to a glow discharge tube which may be used for the amplification, rectification or production of electric oscillations.

5 According to a construction known per se such tubes are provided with a system of electrodes comprising two glow discharge electrodes, viz., a cathode and a first anode between which a glow discharge is produced which serves as a source of electrons for a second discharge current which passes to a second anode, the latter anode drawing to it a portion of the electrons of the glow discharge first above referred to, a controlling electrode being arranged in front of the second anode for the purpose of modulating the amplification current. I have previously proposed in an earlier application to construct the glow discharge anode of such a tube in the form of a plate in such a way that the straight line connections between the cathode and the controlling electrode and the second anode are interrupted. This enables the detrimental grid currents to be greatly reduced. The amplification current which flows to the second anode is then constituted mainly by the electrons which are in the proximity of the edge or edges of the first anode.

20 The present application relates to an improvement on the construction last referred to. According to the invention an intermediate wall is provided between the glow discharge cathode and the glow discharge anode associated therewith, which intermediate wall causes the glow discharge between the cathode and the first anode to be concentrated mainly at the edges of the first anode, whilst the middle parts of the anode which do not come into question for the formation of the amplification current are not impinged upon by parts of the glow discharge.

25

45 The invention is illustrated by way of example in the accompanying drawing in which Figure 1 shows diagrammatically an arrangement of electrodes such as hitherto proposed. Figure 2 is an illustration of the same system of electrodes which is, however, provided with an intermediate wall accord-

ing to the present invention and Figure 3 is a cross section through a complete tube in which the electrodes are arranged concentrically and the discharge electrodes and the intermediate walls are subdivided in a number of individual parts.

In Fig. 1 *k* is a rod-like cathode, *a*₁ is an elongated piece of sheet metal which is indicated in cross-section, *a*₂ is similarly an elongated piece of sheet metal serving as the amplifying anode and *g* is the grid.

In this arrangement a substantially large current passes from *k* to *a*₁, as is indicated in dotted lines, whilst only a small fraction of the current is drawn by *a*₂. In order to avoid this drawback according to the invention, an insulating wall *w* is for instance arranged between *k* and *a*₁, as is indicated in Figure 2. This wall prevents the direct passage of current between *k* and *a*₁ and compels the electrons to move more towards the edges of *a*₁, wherefrom they can be drawn more easily by *a*₂ through the grid *g*.

Figure 3 illustrates a cross section of a complete tube *t* in which four pairs of cathodes and discharge anodes are employed. The discharge anodes *a*₁, are folded over along the longitudinal edge, small mica plates *b* being inserted into and held by the folds.

Instead of using insulating material for the screening walls, metal may be used, in which case, however, care must be taken that the metal walls should be completely insulated from the other electrodes. The metal walls as well as the surfaces of the insulating walls are negatively charged, whereby it is prevented that after charging electrons should pass over to them. If the screening walls *b*, according to Figure 3, or *w* according to Figure 2, are made of metal, they can be led out conductively from the glass foot of the discharge tube and a definite potential can be imparted to them. By suitably choosing the potential, the value of the glow discharge current and consequently of the amplification current which passes over to *a*₂ can be controlled and regulated. If, for instance, the metallic walls *b*, according to Figure 3 or *w* according to Figure 2 receive the same potential as the discharge an-

odes α_1 , this is equivalent to the case in which no intermediate walls are provided. However, if the intermediate walls receive a potential which is negative with respect to α_1 , a screening effect is obtained, which screening effect can be controlled by a regulation of the potential as is desired in each individual case.

What I claim is:—

10 1. A glow discharge tube for the amplification, rectification or production of electric oscillations comprising a discharge cathode and a discharge anode serving as a source of electrons for a current passing to a second anode, a controlling electrode for modulating the said current and an intermediate wall between said cathode and said discharge anode, whereby the discharge between said cathode and said discharge anode is caused 20 to be concentrated near the edges of said discharge anode.

2. A glow discharge tube for the amplification, rectification or production of electric oscillations comprising a discharge cathode 25 and a discharge anode serving as a source of electrons for a current passing to a second anode, a controlling electrode for modulating the said current and an intermediate wall of insulating material between said cathode 30 and said discharge anode, whereby the discharge between said cathode and said discharge anode is caused to be concentrated near the edges of said discharge anode.

3. A glow discharge tube for the amplification, rectification or production of electric oscillations comprising a discharge cathode 35 and a discharge anode serving as a source of electrons for a current passing to a second anode, a controlling electrode for modulating the said current and an intermediate wall of insulating material between said cathode 40 and said discharge anode whereby the discharge between said cathode and said discharge anode is caused to be concentrated 45 near the edges of said discharge anode, the said intermediate wall being made of mica.

4. A glow discharge tube for the amplification, rectification or production of electric oscillations comprising a discharge cathode 50 and a discharge anode serving as a source of electrons for a current passing to a second anode, a controlling electrode for modulating the said current and an intermediate wall of insulating material between said cathode 55 and said discharge anode whereby the discharge between said cathode and said discharge anode is caused to be concentrated near the edges of said discharge anode, the said intermediate wall being made of mica 60 and the said discharge anode being folded over along the edges, the intermediate wall being held within the folds thus formed.

In testimony whereof I have signed my name to this specification.
